UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET COLLECTING AND ASSOCIATING MECHANISM.

Application filed January 18, 1922. Serial No. 530,104.

To all whom it may concern:

Be it known that I, HOWARD M. BARBER, a citizen of the United States, and resident of Stonington, in the county of New London 5 and State of Connecticut, have invented a new and useful Improvement in Sheet Collecting and Associating Mechanism, of which the following is a specification.

The object of my invention is to provide a 10 novel sheet collecting and associating mechanism in which the product of the press is collected and associated with previously printed extra sheets, which may be either covers or inserts or both; the same feeding 15 means being employed for introducing either covers or inserts or both, to be combined with the products of the press, thereby obviating the necessity of using separate feeders for the covers and inserts as has 20 heretofore been common.

A practical embodiment of my invention is represented in the accompanying drawings, in which the sheet collecting and associating mechanism herein illustrated is 25 adapted to collect a full product of forty eight pages and associate therewith the previously printed extra sheets as a cover or an insert; or to collect two one-half products of twenty four pages each and associate 30 therewith the previously printed extra sheets as either covers or inserts, as may be desired.

Fig. 1 represents a detail vertical section showing the delivery and associating cylinders.

Fig. 2 represents a detail vertical section showing the combined collecting and associating cylinder and the first and second extra sheet transfer cylinders as arranged for 40 handling one-half products.

Fig. 3 represents a detail vertical section showing the third transfer cylinder.

Fig. 4 represents a longitudinal vertical section taken through the mechanism at the 45 ends of the cylinders with the side frames removed, the parts being arranged for the run of a full product.

Fig. 5 represents a similar section showing the parts changed for the run of one-half 50 products.

Fig. 6 represents a longitudinal vertical section taken midway through the mechanism with the parts arranged for the run of a full product.

Fig. 7 represents a similar view showing

the parts arranged for the run of one-half products.

Fig. 8 represents the gearing connecting the several cylinders.

I have shown a pair of coacting rotary 60 cutters 1 and 2 of well known construction, arranged to receive superimposed narrow webs from the press and to cut the webs transversely into groups of sheets which are fed through the coacting guide rollers 3 and 65 4 to the collecting and associating cylinder 5. This cylinder 5 is shown as provided with three sets of head grippers 6 and three sets of side grippers 7. The associating cylinder 8 which is arranged to receive the sheets 70 from the cylinder 5 and under certain circumstances from the third extra sheet transfer cylinder to be hereinafter described, is shown as being provided with five sets of head grippers 9.

The delivery cylinder 10 for receiving the 75 collected and associated product and transferring it to any suitable folding mechanism, not shown herein, is shown as being provided with two diametrically opposed 80 sets of head grippers 11.

Portions of two extra sheet feeding mechanisms are represented by 12 and 13, each of which feeding mechanisms may be used for introducing previously printed extra 85 sheets, either as inserts or as covers, as may be desired.

The first, second and third extra sheet transfer cylinders are denoted by 14, 15 and 16 respectively. The extra sheet transfer 90 cylinder 14 is shown as provided with a set of tumbler actuated head grippers 17, arranged to take the extra sheets from the feeder 12 and transfer them to the set of head grippers 18 of the second transfer cylinder 15. This second extra sheet transfer cylinder 15 is also shown as provided with a pair of tumbler actuated head grippers 19 which are arranged to take the extra sheets from the feeder 13. In some instances the 100 set of head grippers 18 are arranged 90° from the set of grippers 19, as shown in Fig. 6, and in some instances this set of grippers 18 are arranged 180° from said set of grippers 19, as shown in Fig. 7, to suit different 105 requirements to be hereinafter set forth.

In some instances the third extra sheet transfer cylinder 16 is provided with one set of head grippers 20 as shown in Fig. 6 and in some instances this third extra sheet 110

transfer cylinder is provided with another set of head grippers 21, as shown in Fig. 7.

A fixed cam 22 is arranged in position to operate the grippers 6 on the cylinder 5 to receive the groups of main press sheets from the feed pulleys 3 and 4. A movable cam 23 is operated by a rotary cam 24, fixed to the shaft 25 of the first transfer cylinder 14. This cam 23 is arranged to control the operation of the grippers 6 of the cylinder 5 for transferring the product to the associating cylinder 8 at the proper time. The rotary cam 24 is a one-lobed cam when a full product is being run, as shown in Fig. 4, and is a two-lobed cam when a one-half product is being run, as shown in Fig. 5.

A movable cam 26 is operated by a rotary cam 27 on the shaft 28 of the second transfer cylinder 15 for operating the grippers 6 on the cylinder 5 for receiving the extra sheets from the second transfer cylinder 15 at the proper time. This rotary cam 27 is a one-lobed cam when a full product is being run, as shown in Fig. 4, and is a two-lobed cam when a one-half product is being run, as shown in Fig. 5. A movable cam 29 is operated by a rotary cam 30 on the shaft 31 of the third transfer cylinder 16 for controlling the operation of the grippers 9 on the associating cylinder 8 to receive the extra sheets from the cylinder 16 at the proper times. This cam 30 is a one-lobed cam when a full product is being run, as shown in Fig. 4, and is a two-lobed cam when a one-half product is being run, as shown in Fig. 5. A movable cam 32 is operated by a rotary cam 33 on the shaft 34 of the delivery cylinder 10, which cam 32 is arranged in position to operate the grippers 9 on the associating cylinder 8 for receiving the products from the collecting and associating cylinder 5 at the proper times. This rotary cam 33 is a one-lobed cam when a full product is being run, as shown in Fig. 4, and is a two-lobed cam when a one-half product is being run, as shown in Fig. 5. A movable cam 35 is operated by a fixed cam 36, see Fig. 1, for controlling the operation of the grippers 9 on the associating cylinder 8 for transferring the products from the cylinder 8 to the delivery cylinder 10 at the proper times. Fixed cams 37, 38 are arranged in position to operate the grippers 11 on the delivery cylinder 10 for receiving the products from the associating cylinder 8 and for delivering the products from the cylinder 10 to any suitable folding mechanism, not shown herein.

Pins 39, 40 are arranged in position to operate the tumbler actuated grippers 17 on the first transfer cylinder 14 for taking the previously printed extra sheets from the feeder 12 and transferring them to the second transfer cylinder 15. Pins 41, 42 are arranged in position to operate the tumbler

actuated grippers 19 on the second transfer cylinder 15 for taking the previously printed extra sheets from the feeder 13 and delivering them to the collecting and associating cylinder 5. A third pin 43 may be placed in position to operate the tumbler actuated grippers 19 for transferring the previously printed extra sheets to the third transfer cylinder 16 when said sheets are to be inserts, when a one-half product is being run. Fixed cams 44, 45 are provided in position to operate the grippers 18 for taking the previously printed extra sheets from the transfer cylinder 14 and transferring them to the third transfer cylinder 16 at the proper times. Fixed cams 46, 47 are arranged in position to operate the grippers 20 on the third transfer cylinder 16 to take the previously printed extra sheets from the second transfer cylinder 15 and transfer them to the associating cylinder 8 at the proper times, when a full product is being run. These cams are also used for operating the grippers 21 which are mounted on the third transfer cylinder 16 when a one-half product is being run.

The sets of side grippers 7 are controlled by fixed cams 18*, whereby the side grippers may be closed onto the groups of sheets when it is desired to open the head grippers 95 for the reception of the extra sheets.

It will be observed that when a full product is being run the grippers 18 and 19 on the second transfer cylinder 15 are arranged 90° apart, as shown in Fig. 6, and when a one-half product is being run the grippers are arranged 180° apart, as shown in Fig. 7.

With a full product being run, in which the previously printed sheets from the feeder 12 are covers and from the feeder 13 are inserts, the cover is fed to the cylinder 5 and the insert is fed to the cylinder 8, as will be hereinafter more fully described.

With a one-half product being run, in which the previously printed extra sheets from both feeders are covers, the covers are fed from both feeders to the cylinder 5; and where the previously printed extra sheets are inserts, the inserts are fed from both feeders to the cylinder 8, as will be herein- 115 after more fully described.

The train of gears for driving the several parts is denoted by 48, 49, 50, 51, 52, 53, 54, 55, 56, the driving gear 56 of the third transfer cylinder being removable for the purpose 120 to be hereinafter described.

I will first describe the operation of the mechanism where a full product is being run with both a cover and a center page insert: The cover is fed from the feeder 12 to the first transverse cylinder 14; from thence to the second transfer cylinder 15, and from thence to the collecting and associating cylinder 5 as the first sheet of the collection. The insert is fed from the feeder 130

- 13 to the second transverse cylinder 15; from thence to the third transfer cylinder 16, and from thence to the associating cylinder 8 where it will be associated on the cylinder 8
 5 with the full product of the press together with the cover sheet. This cylinder 8 will present the full product to the cylinder 10 from which it will be delivered to any suitable folding mechanism, not shown herein.
 10 I will next describe the operation of the mechanism when a one-half product is being run with a cover only:

The cover from the feeder 12 is transferred to the collecting and associating cylinder 5 through the first and second transfer cylinders to be associated with one one-half product, and the cover from the feeder 13 is transferred to the collecting and associating cylinder 5 through the second transfer cylinder 15 to be associated with the next succeeding one-half product. These one-half products are taken by the cylinder 8 and transferred to the delivery cylinder 10, and from thence delivered to the folding mechanism, not shown herein. When running the half products with covers only, the third transfer cylinder 16 is rendered inoperative by removing its driving gear 56. The second transfer cylinder 15 having its two sets 25 of grippers 18 and 19 in this instance, arranged diametrically opposite as shown in Fig. 7.

I will next describe the operation of the mechanism when a one-half product is being run with inserts only:

The inserts from the feeder 12 are transferred to the cylinder 8 through the first, second and third transfer cylinders 14, 15 and 16, in position to be associated with one 40 one-half product collected by the cylinder 5. The insert fed from the feeder 13 is transferred to the cylinder 8 through the second and third transfer cylinders 15 and 16 in position to be associated with the next 45 succeeding one-half product. These one-half products are transferred by the cylinder 8 to the delivery cylinder 10 and delivered by it to the folding mechanism, not shown herein.

50 It is evident that various changes may be resorted to in the construction, form and arrangement of the several parts without departing from the spirit and scope of my invention; hence I do not wish to be limited 55 to the particular embodiment herein shown and described, but

What I claim is:—

1. Two coacting sheet collecting and associating cylinders, two extra sheet supply sources, and means for feeding all of the extra sheets when covers from both sources to one of the cylinders or all of the extra sheets when inserts from both sources to the other cylinder.
- 60 65 2. Two coacting sheet collecting and associating cylinders, two extra sheet supply sources, and means for feeding all of the extra sheets when covers from both sources to one of the cylinders or all of the extra sheets when inserts from both sources to the other cylinder.

ciating cylinders, two extra sheet supply sources, and means for feeding all of the extra sheets when covers from both sources to one of the cylinders or all of the extra sheets when inserts from both sources to the other cylinder, or all of the extra sheets when both covers and inserts from both sources to their respective cylinders.

3. First and second coacting sheet collecting and associating cylinders, two extra sheet supply sources, and means for feeding all of the extra sheets when covers from both sources to the first named cylinder or all of the extra sheets when inserts from both sources to the second named cylinder.

75 4. First and second coacting sheet collecting and associating cylinders, two extra sheet supply sources, and means for feeding all of the extra sheets when covers from both sources to the first named cylinder or all of the extra sheets when inserts from both sources to the second named cylinder, or all of the extra sheets when both covers and inserts from both sources to their respective cylinders.

80 85 5. Two coacting sheet collecting and associating cylinders, two extra sheet supply sources, and coacting extra sheet transfer cylinders for feeding all covers from both sources to one of the first named cylinders or all inserts from both sources to the other of the first named cylinders.

90 95 6. Two coacting sheet collecting and associating cylinders, two extra sheet supply sources, and coacting extra sheet transfer cylinders for feeding all covers from both sources to one of the first named cylinders or all inserts from both sources to the other of the first named cylinders, or covers from one source and inserts from the other source to their respective first named cylinders.

100 105 7. First and second coacting sheet collecting and associating cylinders, two extra sheet supply sources, and coacting extra sheet transfer cylinders for feeding all covers from both sources to the first named cylinder or all inserts from both sources to the second named cylinder.

110 115 8. First and second coacting sheet collecting and associating cylinders, two extra sheet supply sources, and coacting extra sheet transfer cylinders for feeding all covers from both sources to the first named cylinder or all inserts from both sources to the second named cylinder, or covers from one source and inserts from the other source to their respective cylinders.

120 125 9. Two coacting sheet collecting and associating cylinders, three extra sheet transfer cylinders, two extra sheet supply sources arranged to feed the extra sheets to the first and second transfer cylinders respectively, the second transfer cylinder being arranged to also take the extra sheets from the first transfer cylinder and to transfer

all of the sheets from both sources when covers to one of the first named cylinders.

10. Two coacting sheet collecting and associating cylinders, three extra sheet transfer cylinders, two extra sheet supply sources arranged to feed the extra sheets to the first and second transfer cylinders respectively, the second transfer cylinder being arranged to also take the extra sheets from the first transfer cylinder, and the third transfer cylinder being arranged to take all of the extra sheets when inserts from the second transfer cylinder and transfer them to one of the first named cylinders.
15. 11. First and second coacting sheet collecting and associating cylinders, three extra sheet transfer cylinders, two extra sheet supply sources arranged to feed the extra sheets to the first and second transfer cylinders respectively, the second transfer cylinder being arranged to also take the extra sheets from the first transfer cylinder, and the third transfer cylinder being arranged to take all of the extra sheets when inserts from the second transfer cylinder and transfer them to the second named cylinder.
20. 12. Two coacting and sheet collecting and associating cylinders, three extra sheet transfer cylinders, two extra sheet supply sources arranged to feed the extra sheets to the first and second transfer cylinders respectively, the second transfer cylinder being arranged to also take the sheets from the first transfer cylinder and to transfer all of the sheets from both sources when covers to one of the first named cylinders, or when inserts by means of the third transfer cylinder to the other of the first named cylinders.
25. 13. Two coacting sheet collecting and associating cylinders, three extra sheet transfer cylinders, two extra sheet supply sources arranged to feed the extra sheets to the first and second transfer cylinders respectively, the second transfer cylinder being arranged to also take the sheets from the first transfer cylinder and to transfer all of the sheets from both sources when covers to one of the first named cylinders, or when inserts by means of the third transfer cylinder to the other of the first named cylinders.
30. 14. First and second coacting sheet collecting and associating cylinders, three extra sheet transfer cylinders, two extra sheet supply sources arranged to feed the extra sheets to the first and second transfer cylinders respectively, the second transfer cylinder being arranged to also take the sheets from the first transfer cylinder and to transfer all of the sheets from both sources when covers to the first named cylinder or when

inserts, by means of the third transfer cylinder to the second named cylinder.

15. First and second coacting sheet collecting and associating cylinders, three extra sheet transfer cylinders, two extra sheet supply sources arranged to feed the extra sheets to the first and second transfer cylinders respectively, the second transfer cylinder being arranged to also take the sheets from the first transfer cylinder and to transfer all of the sheets from both sources when covers to the first named cylinder or when inserts by means of the third transfer cylinder to the second named cylinder, or when a portion are covers to the first named cylinder, and the rest are inserts by means of the third transfer cylinder to the second named cylinder.

16. A sheet collecting and associating mechanism arranged to run either full or one-half products, comprising two coacting cylinders, two sources of extra sheet supply, and means whereby when a full product is being run with cover and insert, the cover from one source is transferred to one cylinder and the insert from the other source is transferred to the other cylinder; when a one-half product is being run with covers, the covers from both sources are transferred to one cylinder; and when a one-half product is being run with inserts, the inserts from both sources are transferred to the other cylinder.

17. A sheet collecting and associating mechanism arranged to run either full or one-half products, comprising two coacting cylinders, two sources of extra sheet supply, and means whereby when a full product is being run with cover and insert, the cover from one source is transferred to one cylinder and the insert from the other source is transferred to the other cylinder; when a one-half product is being run with covers, the covers from both sources are transferred to one cylinder; and when a one-half product is being run with inserts, the inserts from both sources are transferred to the other cylinder, said transfer means including three transfer cylinders.

18. A sheet collecting and associating mechanism arranged to run either full or one-half products, comprising two coacting cylinders, two sources of extra sheet supply, and means whereby when a full product is being run with cover and insert, the cover from one source is transferred to one cylinder and the insert from the other source is transferred to the other cylinder; when a one-half product is being run with covers, the covers from both sources are transferred to one cylinder; and when a one-half product is being run with inserts, the inserts from both sources are transferred to the other cylinder, said transfer means including three transfer cylinders,

one of which is rendered inoperative when all of the extra sheets are transferred to one of the first named cylinders.

19. A sheet collecting and associating mechanism arranged to run either full or one-half products, comprising two coacting cylinders, two sources of extra sheet supply, and means whereby when a full product is being run with cover and insert, the cover from one source is transferred to one cylinder and the insert from the other source is transferred to the other cylinder; when a one-half product is being run with

covers, the covers from both sources are transferred to one cylinder; and when a 15 one-half product is being run with inserts, the inserts from both sources are transferred to the other cylinder, said transfer means including three transfer cylinders, one of which is rendered inoperative when 20 all of the extra sheets are transferred as covers to one of the first named cylinders.

In testimony, that I claim the foregoing as my invention, I have signed my name this 16th day of January, A. D. 1922.

HOWARD M. BARBER.
